UNITED STATES PATENT OFFICE.

RANDOLPH LANGSETH, OF HAMMOND, INDIANA, ASSIGNOR, BY MESNE ASSIGNMENTS,
TO AUTOMATIC JUSTIFIER COMPANY, OF HAMMOND, INDIANA, A CORPORATION OF
INDIANA.

PAGE COMPRESSOR AND JUSTIFIER.

1,130,829.

Specification of Letters Patent.

Patented Mar. 9, 1915.

Application filed August 22, 1913. Serial No. 786,084.

To all whom it may concern:

Be it known that I, RANDOLPH LANGSETH, a citizen of the United States, residing at Hammond, county of Lake, State of Indiana, have invented a certain new and useful Improvement in Page Compressors and Justifiers, and declare the following to be a full, clear, and exact description of the same, such as will enable others skilled in the art 10 to which it pertains to make and use the same, reference being had to the accompanying drawings, which form a part of this specification.

In the art of printing the type is first set 15 up to form a column or page and is then clamped in a form in order to print therefrom. The page or column usually consists of a large number of transverse rows which loosely engage with each other, so that when 20 the composition is clamped in the form, more or less compression and shrinkage in the length of the page or column takes place. The amount of shrinkage varies for different 25 columns or pages and therefore there will not be uniformity between the various pages of a publication made up of a plurality of pages, unless each page is accurately justified. The justifying of a page of composition, in order to secure accuracy in length 30 is a slow and tedious process, and consequently an expensive one.

The object of the present invention is to provide means for conveniently compressing a page or column of composition and indicating exactly the amount of shortage in the 35 page or column, in such units as to enable the compositor to select instantly the necessary lead or leads to bring the page to the exact size desired.

40 The various features of novelty whereby my invention is characterized will herein-after be pointed out with particularity in the claims; but, for a full understanding of my invention and of its object and advan- 45 tages, reference may be had to the following detailed description taken in connection with the accompanying drawings, wherein:

Figure 1 is a top plan view of an apparatus arranged in accordance with a preferred form of my invention; Fig. 2 is a section on an enlarged scale taken on line 2—2 of Fig. 1, a portion of the apparatus between the ends being broken away; Fig. 3 is a section on line 3—3 of Fig. 1, the scale

being the same as that of Fig. 2, and the 55 central portion of the apparatus being broken away; Fig. 4 is a section taken approximately on line 4—4 of Fig. 1; Fig. 5 is a section taken on the line marked 5—5 in Fig. 3; and Fig. 6 is a fragment of the apparatus looking at the right hand end of Fig. 3.

Referring to the drawings, 1 is a flat table, preferably of metal, having near the front edge an upwardly-projecting ledge, 2, and 65 at one side an upwardly-projecting ledge, 3, the two ledges being arranged accurately at right angles to each other and being provided with scales, 4 and 5, graduated with the pica as a unit. The page or column is 70 adapted to be set up on the table in the corner formed by the two ledges, or it may be placed on the table after it has been set up. Movable lengthwise of the ledge 2 and parallel with the ledge 3 is a presser foot 75 or gage, 6, which is adapted to be brought up against the end of a page or column of matter on the table and compress it. With the member 6 is associated a suitable indicator which will show the exact amount 80 which the compressed column or page lacks in order to give it exactly the desired length.

In the particular arrangement illustrated, the member 6 has in its under face a groove, 7, fitting over the ledge 2 so as to permit the 85 member 6 to be slid along the ledge and remain always at right angles thereto with the main portion thereof resting upon the table. In the top of the ledge 2 is a trough or depression, 8, extending from one end of 90 the ledge to the other.

9 is a screw threaded shaft lying in the depression or trough 8 and supported at its ends in suitable bearings, 10 and 11, forming part of or rigidly connected with the 95 ledge 2.

The member 6 has a boss, 12, extending down into the depression 8 and provided with an opening, 13, through which the screw shaft extends, the diameter of the 100 opening being the same as the outside diameter of the screw shaft. A section of the member 6 just above the opening 13 is cut away so as to allow a dog, 14, pivoted upon the upper side of the member 6 to project 105 down into the opening. The portion of the dog 14 which projects into the opening 13 is provided with screw threads meshing

with the threads on the shaft 9. The dog 5 may be normally held in a position wherein its screw threads engage with the screw threads on the shaft by a suitable spring, 15; and it may be provided with a finger piece or handle, 16, by which the dog may be raised against the tension of the spring so as to bring it clear of the shaft. It will 10 be seen that when the dog is down, the combined presser foot and gage is interlocked with the screw shaft so that it cannot be moved lengthwise of the shaft unless there be a relative angular movement between the two. On the other hand, when the dog is 15 raised, the combined presser foot and gage may be moved lengthwise of the shaft and independently of the latter.

On the end of the screw shaft farthest removed from the ledge 3 is a bevel pinion, 18, meshing with a bevel gear, 19, carried by a sleeve, 20, which is adapted to rotate on a vertical post, 21, fixed to the table. For a reason which will hereafter appear, the bevel gear 19 is preferably made with 25 twice as many teeth as the pinion 18 so that half a revolution of the gear corresponds to a complete revolution of the pinion. On the upper end of the sleeve 20 is a disk, 22, one edge having a radial extension, 23, provided with a handle, 24. The upper end of 30 the post 21 is made conical as indicated at 25, and about this conical portion of the post fits the hub, 26, of a graduated dial, 27. On the disk, preferably on the radial 35 extension 23, is a pointer, 28, which projects into proximity to the dial. The dial is divided on its upper face into twenty-four equal parts by lines, 29. Beginning with one of the lines they are numbered in opposite 40 directions, beginning with a zero, from 1 to 12, so that the dial may be said to have two sets of graduations reading in opposite directions. By supporting the dial on the conical upper end of the post, it is frictionally held in place so as normally to be a stationary part, but it may be lifted slightly 45 so as to turn it in order at any time to bring the zero point in registration with the pointer.

50 The operation is as follows: 30 representing a column or page of typographical matter resting against the ledges 2 and 3, the handle 16 is depressed so as to raise the dog 14 out of engagement with the screw shaft 55 and the combined presser foot and gage is then slipped along the ledge 2 until it engages with the end of the typographical matter. Upon releasing the handle 16, the dog is brought into operative engagement 60 with the screw shaft and, by turning the handle 24, the member 6 may be forced against the end of the typographical matter so as to compress the same between the member 6 and the ledge 3. The dial, 27, is 65 then lifted from its seat on the supporting

post and is turned until the zero mark registers with the pointer 28. The handle 24 is now turned backward so as to back the member 6 away from the typographical matter until its edge registers with the mark 70 on the scale 4 which corresponds to the exact length which the page or column of typographical matter should have. By making the pitch of the threads on the screw shaft one pica, it will be seen that a half revolution 75 of the dial corresponds to a movement of the member 6 through a distance equal to one pica. Assuming that the compressed typographical matter is shorter than the desired page by an amount less than one 80 pica, the pointer will move over the dial through an angle less than 180 degrees while the member 6 is being backed away to the mark on the ledge 2 indicating the exact page length. The dial therefore indicates 85 in fractions of one-twelfth of a pica the shortage of the typographical matter and indicates the number of unit thicknesses of leads which must be inserted in the typographical matter to bring the compressed 90 page or column to exactly the desired length.

Instead of first compressing the typographical matter and then backing the member 6 away, the member 6 may first be brought to the mark on the ledge 2 indicating the exact length of the column or page, the zero point on the dial be brought into registration with the pointer, and the member 6 be then moved toward the typographical matter so as to compress the same; 100 the reading on the dial being the same as before except that the reading is in the opposite direction from the zero point from the reading obtained by backing away the combined presser foot and gage. 105

By having ledges or spacers corresponding in thickness to the units represented by the graduations on the dial or to the multiples of such units, the typographical matter may be justified very quickly and with 110 the assurance that it will be exact.

It is desirable to be able to slide the typographical matter off the end of the table at which the ledge 3 is located, receiving it in a tray or other suitable device without disturbing it. I therefore make the ledge 3 movable, so that it may be carried out of the way when desired. Since the typographical matter is compressed by forcing it against the ledge 3, it is necessary that the latter be 120 rigidly held when in its working position. I am able to move the ledge out of the way quickly and at the same time make it a rigid abutment when in the working position, by fitting it into a vertical slot in the table, 125 making it of considerable depth to give it a firm lateral support below the plane of the top of the table. The ledge may conveniently be moved and be locked in its raised position by having a shaft, 31, extending 130

through depending flanges, 32 and 33, on the table and passing lengthwise through the ledge, the shaft having thereon eccentrics, 34, arranged in suitable pockets in the ledge. On the front end of the shaft is a handle, 35, by means of which it may be turned. On the rear end of the shaft is a radial pin, 36, which co-operates with two stationary pins, 37 and 38, on the flange 33 of the table so as to permit the shaft to be oscillated through an angle of 180 degrees. The parts are so proportioned that when the shaft 31 is at one limit of its angular movement, the highest point on the eccentric is directly above the axis of the shaft. Therefore, when the shaft is at the other limit of its angular movement, the lowest point of the eccentric is directly above the axis of the shaft. The throw of the eccentric is just equal to the height of the ledge 3 above the table. Consequently when the handle 35 is turned in one direction as far as it will go, the ledge 10 is raised and is locked in its raised position and when the handle is turned as far as it will go in the opposite direction the ledge is lowered until its upper surface is flush with the upper surface of the table and forms a continuation of the table across which the typographical matter may be slid without encountering any obstruction.

While I have illustrated and described with particularity only a single preferred form of my invention, I do not desire to be limited to the exact structural details thus illustrated and described; but intend to cover all forms and arrangements which fall within the definitions of my invention constituting the appended claims.

40 I claim:

1. In an apparatus of the character described, a table adapted to support a body of typographical matter, mechanism on the table for compressing said body, and means co-operating with said mechanism to indicate the difference in length between said body and a predetermined arbitrary unit.

2. In an apparatus of the character described, a table adapted to support a body of typographical matter, a graduated ledge on the table, mechanism co-operating with said ledge to compress a body of typographical matter lying on the table adjacent to the ledge, and means co-operating with said mechanism to indicate the distance between the end of the compressed body and a predetermined point on the ledge.

3. In an apparatus of the character described, a table, a graduated ledge on the table, a combined presser foot and gage slid-able along the ledge and projecting across the table, a screw shaft lying beside and ex-tending throughout the length of said ledge for actuating the combined presser foot and gage, and an indicator connected to said

screw shaft, said indicator being graduated to represent fractional parts of the scale unit on the ledge.

4. In an apparatus of the character de-scribed, a table, a graduated ledge on the 70 table, a combined compressor and gage de-vice slidable along the ledge and projecting across the table, an actuating screw for said device lying parallel with the ledge, an in-dicator connected with said screw and 75 graduated so as to indicate fractional parts of a unit of the scale on the ledge, and means for adjusting said indicator so as to make it possible to set it at zero regardless of the position of said device along the ledge. 80

5. In an apparatus of the character de-scribed, a table, two ledges arranged at right angles to each other upon the table, a com-bined presser and gage device slidably 85 mounted on one of the ledges and extending across the table parallel with the other ledge, and means for supporting the latter ledge so as to permit it to be retracted sufficiently to bring its upper face into the plane of the top of the table. 90

6. In an apparatus of the character de-scribed, a table, a graduated ledge on the 95 table, a combined presser foot and gage slid-able along the ledge and projecting across the table, a screw shaft lying beside the 100 ledge, an indicator connected to said screw shaft, said indicator being graduated to represent fractional parts of the scale unit on the ledge, and a dog movably mounted on said combined presser foot and gage in posi-tion to be moved into and out of engagement with said screw shaft.

7. In an apparatus of the character de-scribed, a table having thereon two ledges arranged at right angles to each other, one 105 of said ledges being graduated, a screw shaft extending lengthwise of and beside the graduated ledge, means for actuating said screw shaft, a combined presser foot and gage slidably mounted on the graduated 110 ledge and extending across the table at right angles to the other ledge, said combined presser foot and gage being provided with screw threads meshing with the threads on said shaft. 115

8. In an apparatus of the character de-scribed, a table, a graduated ledge on the 120 table, a combined presser foot and gage slid-able along the ledge and projecting across the table, said ledge having a groove ex-tending lengthwise thereof in its upper face, a screw shaft lying within said groove for actuating said combined presser foot and gage, and means for actuating said shaft.

9. In an apparatus of the character de-scribed, a table, a graduated ledge on the 125 table, a combined presser foot and gage slid-able along the ledge and projecting across the table, said ledge having a groove ex-tending lengthwise thereof in its upper 130

face, a screw shaft lying within said groove for actuating said combined presser foot and gage, and an indicator connected to said shaft, said indicator being graduated to represent fractional parts of the scale unit on the ledge.

10. In an apparatus of the character described, a table adapted to support a body of typographical matter, a graduated ledge on the table, a combined presser foot and gage slideable along the ledge and projecting across the table, a screw shaft lying parallel with said ledge for actuating the combined

presser foot and gage, means for actuating said shaft including a part revoluble about an axis at right angles to the shaft, and a stationary disk arranged co-axial with said part and having a graduated ledge lying in proximity to said part.

In testimony whereof, I sign this specification in the presence of two witnesses.

RANDOLPH LANGSETH.
